Cincinnati.

UNITED STATES PATENT OFFICE.

WILLIAM S. WESTON, OF COLUMBIA, SOUTH CAROLINA.

LOCKING DEVICE FOR MANTLE NUTS.

Application filed July 19, 1922. Serial No. 576,146.

To all whom it may concern:

Be it known that I, WILLIAM S. WESTON, a citizen of the United States, and residing at Columbia, Richland County, State of 5 South Carolina, have invented certain new and useful Improvements in Locking Devices for Mantle Nuts, of which the following is a specification.

The present invention relates to gyratory 10 crushing machines and particularly to means for preventing jamming of the mantle nuts of such machines.

In gyratory crushing machines it is customary to provide, above the mantle of the 15 crushing cone secured to the main gyratory shaft, a mantle nut having threaded engagement with the shaft, to prevent the mantle from moving vertically upward, and to protect the upper end of the mantle from being 20 injured by the stone passing downwardly through the machine. It has been frequently found, in cases where the annular lower edge of the mantle nut has had full bearing on the annular upper edge of the 25 mantle, that due to the action of the stone on the nut as the shaft gyrates, the nut has been turned down so tightly that its removal by unscrewing has been impossible. In such cases it is necessary to cut away the 30 mantle nut when the mantle is to be removed and to replace it by a new one. This involves considerable loss of time and the cost of a new nut.

It is the object of the present invention to 35 provide means to be interposed between the mantle and mantle nut whereby the full holding power of the nut on the mantle is retained, but which prevents the nut from being jammed on the mantle to such an extent that its removal cannot easily be accomplished. The means employed consists in a series of members having surfaces 40 adapted to bear against the lower edge of the mantle nut and against the upper edge 45 of the mantle to prevent seating of the mantle nut on the mantle so that these members are separated, when the nut has been screwed into position, by a small annular gap and the nut is positively locked to the 50 mantle in such manner as to keep the latter tight on the shaft.

One form of the invention is illustrated 55 in the accompanying drawings and described in the following paragraphs, by way of example.

In the drawings:

Fig. 1 is a side elevation, partly broken away, of the upper end of the crushing cone of a gyratory crusher showing the mantle, mantle nut, and the manner in which 60 these members are mounted on the shaft.

Fig. 2 is a section on line 2—2 of Figure 1;

Fig. 3 is a section on line 3—3 of Figure 1.

The gyratory shaft is indicated at 10, the mantle at 11 and the mantle nut at 12. The 65 core 10', having its external surface in the form of a frustum of a cone, is pressed upon the shaft 10 so as to be rigidly united therewith. The inside surface of the mantle 11 is similar to the external surface of the 70 core 10', but the cone formed by the former is somewhat larger, and the intervening space is entirely filled by the zinc layer 13 thus securing the mantle to the core and shaft. The mantle nut 12 has a right hand 75 thread and is in threaded engagement with the threaded portion 14 of the shaft. The nut has a frusto-conical in shape and has longitudinal ribs 15 on its outer surface so that wrenches or special tools may grip the same 80 to effect its rotation on the shaft. The nut has a plurality of notches or recesses 16 having inclined upper edges 17 and the upper edge of the mantle 11 is provided with a plurality of recesses 18, the recesses 16 and 85 18 being in register, as shown in Figure 1, when the nut 15 is in position.

A plurality of keys 19 extend into these registering recesses, these keys having inclined surfaces 20 to bear against surfaces 90 17 of the mantle nut and having surfaces to bear against the walls of recesses 18. The keys are also provided with tongues or extensions 21 extending downwardly, as shown in Figure 3 and in dotted lines in 95 Figure 1, in rear of the mantle so that the keys cannot be displaced accidentally.

The keys 19 prevent the annular bearing surface of the nut from contacting with the annular upper surface of the mantle, all of 100 the pressure between the mantle and the nut being taken upon the upper slope of the wedge 19. Jamming of the nut upon the mantle is thus prevented, and the great reduction in the contacting area of the nut 105 renders it much easier to remove. When it is desired to remove the nut, it is only necessary to strike it a few blows with a driving bar and sledge hammer in a direction opposite to that of the arrow A of Fig. 110

1. Since the pitch of the right-handed threads on the nut and shaft is much less than the pitch of the upper slope of the wedge or key 19, the slightest motion of the 5 nut in that direction separates the surfaces 17 and 20. The wedges may then be lifted slightly and removed from their apertures, and the nut is free to be removed from the shaft by unscrewing it with a spanner 10 wrench or by hand.

The great force exerted by the rock on the crushing mantle causes, in course of time, the zinc lining 13 to flow upwardly and to contact with the lower edge of the mantle 15 nut. As a full contact between the zinc and mantle nut would render it difficult to remove the nut, I provide an annular groove 22 in the lower edge of the mantle nut and directly over the annular upper edge of the 20 zinc filler. The zinc will not flow into this groove and the mantle nut will thus prevent the zinc from escaping without being materially bound thereby against turning.

When the crushing machine is in operation, the shaft is gyrated by an eccentric in a clockwise direction as seen when looking down on the top of the machine. This causes a slight rotation of the shaft in a counter-clockwise direction, as shown by the 25 arrow A of Fig. 1. The crushing of the rock between the mantle and the frame of the machine, however, resists this rotation and exerts a clockwise force on the mantle in the direction of the arrow B of Fig. 1. 30 The result, therefore, is a tendency for the mantle to creep clockwise with respect to the core and shaft. If the mantle is thoroughly tight on the zinc, and the zinc in turn thoroughly tight on the core, such slippage 35 or creeping will not take place, the core being, as a result of the construction above described, practically a unit with the shaft. If, however, a slight looseness does develop, due to the flowing of the zinc, the mantle 40 will be automatically tightened again on the core. A slight creeping will take place between the mantle and the core, but the construction of the keys 19 is such that the mantle nut will be locked to and forced to 45 move with the mantle during this clockwise creeping. The net result, therefore, is a rotation of the mantle and nut, as a unit, relative to the core and shaft as a unit, which rotation screws the nut down on the 50 shaft. The mantle is thus forced further down on the conical core, thereby taking up the looseness and increasing the friction between the parts sufficiently to prevent further creeping.

55 The keys 19 will thus be seen to serve two main purposes. First, they prevent the nut from becoming jammed against the mantle by the force exerted by the rocks during the crushing operation; and greatly decrease the 60 area of contact of the lower face of the nut,

thereby rendering the nut much easier to remove. Second, the keys lock the nut to the mantle so as to force it to move with the mantle during any creeping movement of the latter, thereby automatically re-tightening 70 the mantle on the core.

To one skilled in the art the advantages of the key locking device above described will be apparent, and it will also be obvious that the parts may be designed in different 75 ways without departing from the scope of the invention.

Having thus described the invention what is claimed as new and desired to be secured by Letters Patent is:

1. In a device of the class described, in combination, a shaft having a threaded portion, a mantle mounted on the shaft, a mantle nut having threads interengaging with the threads on the shaft, and a device 85 interposed between the nut and mantle, said device preventing contact of the mantle and nut and causing the nut to move with the mantle during movement of the latter in one direction.

2. In a device of the class described, in combination, a shaft having a threaded portion, a mantle mounted on the shaft, a mantle nut having threads interengaging with the threads on the shaft, and a device 95 interposed between the nut and mantle, said device having a wedge shaped portion, the faces of which bear against the mantle and nut respectively; and said device preventing contact of the mantle and nut.

3. In a device of the class described, in combination, a shaft having a threaded portion, a mantle mounted on the shaft, a mantle nut having threads interengaging with the threads on the shaft, and a device 105 interposed between the nut and mantle, said device having a portion interlocking with the mantle so as to be held against movement circumferentially of the mantle, and preventing contact of the mantle and nut and locking the nut to the mantle so that the two move together whenever the latter creeps upon the shaft, the nut and shaft being so threaded that this movement results in a tightening of the mantle upon 110 the shaft.

4. In a device of the class described, in combination, a shaft having a threaded portion, a mantle mounted on the shaft, a mantle nut having threads interengaging with the threads on the shaft, and a device 120 interposed between the nut and mantle, said device having a surface inclined to a plane at right angles to the axis of the shaft adapted to bear against a corresponding inclined surface of the nut, and preventing contact of the nut and mantle.

5. In a device of the class described, in combination, a shaft having a threaded portion, a mantle mounted on the shaft and 130

having a recess in its upper edge, a mantle nut having threads interengaging with the threads on the shaft and having an elongated recess in its lower edge, and a wedge device insertable into said recesses when in register for holding the mantle and nut out of contact.

6. In a device of the class described, in combination, a shaft having a threaded portion, a mantle mounted on the shaft, a soft metal lining between the mantle and the

shaft, and a mantle nut having threads interengaging with the threads on the shaft, said nut having an annular lower end surface and an annular groove in said lower end surface in position to reduce the surface of said mantle nut bearing on said soft metal lining, as and for the purpose described.

In testimony whereof I hereunto affix my signature.

WILLIAM S. WESTON.
